UNITED STATES PATENT OFFICE.

ROY W. YOUNG, OF ELMORE, MINNESOTA.

PROTECTIVE DEVICE FOR FENCES.

Application filed March 14, 1924. Serial No. 699,255.

To all whom it may concern:

Be it known that I, Roy W. Young, a citizen of the United States, residing at Elmore, in the county of Faribault and State 5 of Minnesota, have invented new and useful Improvements in Protective Devices for Fences, of which the following is a specification.

This invention relates to fence attachments and has for its object the provision of a novel device of a brace like nature adapted for engagement upon a wire fence of any kind for preventing the fence wire from being forced downwardly by animals, 10 the device being equally well suited for use on fences of barbed or other line wire or a combination of woven and barbed there being no restriction in this respect.

Another object is the provision of a brace 20 which is formed from a single length of heavy gage wire or light rod, and which, when once placed in position will remain until positively and intentionally removed.

An additional object is the provision of 25 an attachment of this character which will be simple and inexpensive in manufacture, easy to apply, positive in action, efficient and durable in service and a general improvement in the art.

With the above and other objects and 30 advantages in view the invention consists in the details of construction to be herein-after more fully described and claimed and illustrated in the accompanying drawings, 35 in which:

Figure 1 is an elevation of a fence with my device applied,

Figure 2 is a detail view of the device alone.

Referring more particularly to the drawings the letter A represents fence posts forming part of a fence constructed of woven wire B above which are two strands of barbed wire C. This is simply for purpose of illustration as it is obvious that the 45 device is equally well usable on fences constructed entirely of line wires or entirely of woven wire.

In carrying out the invention I provide a brace designated broadly by the numeral 50 10, which brace is formed from a single length of wire of heavy gage or rod of light gage, bent and rebent as shown at 11 and 12 respectively at each end to define hooks 13. Intermediate its ends, the 55 wire or rod is formed with a convolution 14 which is left slightly open for engage-

ment upon the lower wire C. In applying the device, the convolution or loop 14 is first engaged upon the lower wire C, one hook 13 is engaged with the top most strand 60 of the woven wire section B and the other hook 13 is engaged upon the upper wire C. The wires engage within the first bends 12 of the hooks and it is therefore obvious that the brace will reinforce the fence and 65 positively prevent the wires from being forced down out of place upon the exertion of pressure by animals. The device is bound to prolong the life of a fence and keep it in good condition. As the brace 70 is formed from a single piece of wire or the like, it is evident that the cost of production will be negligible as compared with the benefits derived from its employment.

While I have shown and described the 75 preferred embodiment of my invention it is of course to be understood that I reserve the right to make such changes in the form, construction and arrangement of parts as will not depart from the spirit of the invention or the scope of the subjoined claims.

Having thus described my invention I claim:

1. Means for bracing a wire fence, comprising an elongated member formed from 85 a single length of resilient wire coiled intermediate its ends to define an eye adapted to be engaged with one wire of a fence, the end portions being bent backwardly and then rebent to define hooks engageable with 90 adjacent wires of the fence.

2. A fence brace comprising an elongated member formed from a single length of resilient wire coiled intermediate its ends to define an eye engageable with one wire 95 of a fence, said length of wire having its end portions bent backwardly toward each other and rebent with the terminals lying within the first mentioned bends whereby to define retaining hooks adapted for engagement with wires at opposite sides of the first named wire.

3. A brace of the character described formed from a single length of resilient material provided centrally with a loop 105 adapted for engagement upon one wire of a fence and formed at both ends with reflexly extended portions defining hooks engageable with other wires of a fence for holding the wires relatively rigid.

In testimony whereof I affix my signature.
ROY W. YOUNG.
